UNITED STATES PATENT OFFICE.

ISADORE DAVID WOLFSON, OF NEW YORK, N. Y., ASSIGNOR TO I. D. WOLFSON, INC., A CORPORATION OF NEW YORK.

NECKTIE.

1,300,682.

Specification of Letters Patent. Patented Apr. 15, 1919.

Application filed May 22, 1914. Serial No. 840,181.

To all whom it may concern:

Be it known that I, ISADORE DAVID WOLFSON, a citizen of the United States, and resident of New York city, borough of Manhattan, in the State of New York, have invented certain new and useful Improvements in Neckties, of which the following is a specification.

The object of this invention is to provide an easily-manipulated and durable necktie, and one in which there is economy of the expensive material forming the body of the tie.

In the accompanying drawing,

Figure 1 is a perspective view of a necktie embodying the invention, and

Figs. 2, 3, 4 and 5 are respectively sections through the tie on lines 2—2, 3—3, 4—4, and 5—5 of Fig. 1.

Similar characters of reference indicate corresponding parts throughout the drawing.

This necktie consists of a neckband and two tying ends and comprises in the embodiment herein shown a face-strip 10, a lining-strip 21 and a filling 24. The face-strip 10 is composed of any suitable material, which may be bias-cut, as shown at 30. The material of this strip is the most expensive that is customarily put into the manufacture of the tie, as it is the portion which is exposed to view when the necktie is in use. The face-strip 10 is folded or turned along its opposite edges 11 and 12 over upon itself forming overlapping marginal flaps 14 and 15 at the back of the tie. These marginal flaps are very narrow along the neckband and somewhat broadened along those portions of the tying ends which are adjacent to the neckband.

The lining-strip 21 is preferably of straight-cut material of less value than the more expensive material of the face-strip. This lining-strip is of a stronger material, resistant to the strains of use. This lining-strip is folded or turned along its edges under upon itself forming inturned attaching flaps 16 and 17. The lining-strip 21 is placed at the back of the face-strip 10 with its inturned attaching flaps 16 and 17 resting on the inner portions of the overlapping marginal flaps 14 and 15 of said face-strip and stitchings 23 and 27 unite the overturned flaps 14 and 15 of the face-strip with the inturned flaps 16 and 17 of the lining-strip.

These stitchings do not extend through the body or outer portion of the lining-strip 21; neither do they extend through the body or outer portions of the face-strip 10, but are covered and concealed by said outer portions. The folded edges of the face-strip 10 extend beyond the folded edges of the lining-strip 21, the folded edges of the face-strip being exposed at the back of the tie outside the lining-strip, and marginal stitchings 20 unite the layers thereof along the back of the neckband outside the stitchings 23 and 27 which unite the folded face-strip with the folded lining-strip. The opposite ends or terminals of the lining-strip 21 are tapered forming points 40 as shown in Fig. 1 and the folds of the face-strip 10 are broadened and meet beyond these terminals. The meeting edges of the overturned face-strip are preferably stitched together by 75 marginal stitchings 22 for a short distance beyond said terminals and thence are unstitched through the remainder of the tie ends as usual in ties of this style. Short cross stitchings 36 unite the meeting edges 80 of the face-strip at the back of the tie where the lining-strip terminates.

The filling 24 is of a width corresponding with the folded face-strip 10 and extends into the marginal flaps thereof beyond the 85 concealed stitchings 23 and 27 which unite the face-strip with the lining-strip and the outer stitchings 20 penetrate the outer margins of said filling and firmly unite it with the folded edges of the face-strip. 90

The tie thus constructed has a multiplicity of layers (five more or less) along the tie adjacent to the opposite edges thereof. These layers practically form slide ribs near opposite edges of the tie which facilitate the 95 movement within the collar, and the lateral extensions of the folded face-strip beyond said ribs avoid wear at the edges of the tie, and the stitchings in these folded edges outside said ribs maintain the shape of the tie 100 and prevent the wrinkling thereof under the strain of sliding adjustment within the collar.

The lining-strip 21 gives a really smooth and slip-easy continuous band over the whole 105 length of the tie.

A straight-cut lining-strip when inserted in a bias-cut tie makes the tie really a straight tie.

The lining-strip 21 is thin and eliminates 110

the customary single bulky seam in center or at the side of the ordinary tie.

The tie is cheaper to construct, as the whole tie is put together in one operation, 5 including the lining-band 21; it is all made by machine, no hand-stitching being necessary in the construction of the tie.

There is a saving of the expensive material, by the inserting of the cheap smooth 10 lining material, which saves the better material on the face of the tie.

Ties are made cheaper, with this lining, as no hand-slip stitching, which is weak and expensive to make, is required in the making 15 of this tie, and at the same time the lining gives the tie the appearance of a hand-slip stitched scarf instead of a machine-stitched scarf.

The lining-band 21 is inserted in the operation of making the tie, instead of as an 20 extra and separate operation of inserting the lining after the tie is otherwise completed.

The tie is made very sightly and neat at the back by the lining-band 21 being inserted, owing to the fact that there are no exposed 25 stitches and no exposed edges, as everything is taken inside.

A strong, reinforced, straight-cut, non-yielding lining-band is provided, over the 30 whole length of the tie, set in by machine-stitches that are not visible, and which will stay longer and are less liable to fray out than hand-stitches.

The lining-band keeps the tie from twisting 35 or wrinkling or pulling out of shape, as it is a straight-cut band that holds the bias silk face material from pulling.

The cross-stitches 36 at each end of the lining-band passing through the facing material, the lining and the filling, add to the 40 reinforcing and non-yielding qualities of the lining-band.

The lining-strip or band 21 reinforces the knot, when the tie is tied up for use, as it extends in the material of the knot at both 45 the top and bottom of the same, due to the length of the lining-strip along the tie.

The lining strip or band 21 may be made of smooth satin, the individual strips being cut out of one piece, as, for instance, thirty-six strips from one yard of material. Or, where special freedom of movement of the tie in the collar is required, more expensive material, such as ribbon having a specially smooth surface, may be used. The lining-band is not limited in its application to any 50 certain form of tie, but may be employed in four-in-hand, Ascot or other neckties, having both ends alike or different, as the case may be.

One embodiment of the invention has been described, but it is obvious that changes may be made therein without departing from the spirit of the invention.

I claim:

A necktie consisting of a neckband and two tying ends and comprising a face-strip having its opposite edges overturned along the neckband forming marginal folds, and a lining-strip of antifriction material of a 70 width substantially less than the width of the neckband portion having its opposite edges under-turned forming marginal folds narrower than the folds of the face-strip, said strips being secured together by concealed stitching passing through the turned flaps thereof.

In testimony, that I claim the foregoing as my invention, I have signed my name in presence of two subscribing witnesses.

ISADORE DAVID WOLFSON.
